(57) **CLAIM**

The ornamental design for a glass sheet, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a glass sheet showing our new design;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a partial enlarged view of FIG. 1;

FIG. 8 is a front view of another embodiment thereof;

FIG. 9 is a rear view thereof;

FIG. 10 is a top plan view thereof;

FIG. 11 is a bottom plan view thereof;

FIG. 12 is a right side view thereof;

FIG. 13 is a left side view thereof; and,

FIG. 14 is a partial enlarged view of FIG. 8.

The surfaces not bound by evenly spaced broken lines shown in FIGS. 1, 3 and 7 form part of the claimed design as shown. The remainder of the surfaces which are bound by evenly spaced broken lines and shown in reduced opacity as well as the evenly spaced broken lines form no part of the

(Continued)

claimed design. The dot-dash broken lines represent the bounds of the enlarged views and form no part of the claimed design.

1 Claim, 14 Drawing Sheets
